(57) **CLAIM**

The ornamental design for a magnetic panel for air conditioner, as shown and described.

DESCRIPTION

1. Magnetic panel for air conditioner

1.1 : Perspective

1.2 : Perspective

1.3 : Front

1.4 : Back

1.5 : Right

1.6 : Left

1.7 : Top

1.8 : Bottom

Fig. 1.1 is a top perspective view of the magnetic panel for air conditioner; Fig. 1.2 is a bottom perspective view of the magnetic panel for air conditioner; Fig. 1.3 is a front view of the magnetic panel for air conditioner; Fig. 1.4 is a rear view of the magnetic panel for air conditioner; Fig. 1.5 is a right view of the magnetic panel for air conditioner; Fig. 1.6 is a left view of the magnetic panel for air conditioner; Fig. 1.7 is a top view of the magnetic panel for air conditioner; Fig. 1.8 is a bottom view of the magnetic panel for air conditioner; The broken lines in the drawings illustrate the environment of the magnetic panel for air conditioner which forms no part of the claimed design.

1 Claim, 8 Drawing Sheets
